Inventor

W. T. Hunter

By Watson E. Coleman
Attorney

UNITED STATES PATENT OFFICE.

WILLIAM T. HUNTER, OF CHICAGO, ILLINOIS.

DISPENSING APPARATUS.

Application filed December 31, 1921. Serial No. 526,339.

To all whom it may concern:

Be it known that I, WILLIAM T. HUNTER, a citizen of the United States, residing at Chicago, in the county of Cook and State 5 of Illinois, have invented certain new and useful Improvements in Dispensing Apparatus, of which the following is a specification, reference being had to the accompanying drawings.

10 This invention relates to certain improvements in dispensing apparatus and has relation more particularly to a device of this general character especially designed and adapted for use in connection with letter 15 sheets and envelopes, and it is an object of the invention to provide a novel and improved device of this character of a single delivery type and wherein the mechanism for delivering letter sheets is operable independently of the mechanism for effecting a delivery of the envelopes, and vice versa. Another object of the invention is to provide a novel and improved device of this 20 general character wherein the delivery mechanism for either the letter sheets or for the envelopes includes a feed roller produced from a cellular material, preferably sponge rubber, which, as the roller engages the letter sheet or envelope to be delivered, creates 25 a vacuum whereby the delivery of a sheet 30 or envelope is materially facilitated.

Furthermore, it is an object of the invention to provide a novel and improved device of this general character wherein the 35 sheets or envelopes to be delivered are arranged in a pile, together with a mechanism for singly delivering a sheet or envelope from the pile and wherein means is provided for coaction with the pile to assure 40 such single delivery.

The invention consists in the details of construction and in the combination and arrangement of the several parts of my improved dispensing apparatus whereby certain 45 important advantages are attained and the device rendered simpler, less expensive and otherwise more convenient and advantageous for use, as will be hereinafter more fully set forth.

50 The novel features of my invention will hereinafter be definitely claimed.

In order that my invention may be the better understood, I will now proceed to describe the same with reference to the accompanying drawings, wherein:

Figure 1 is a view in perspective illustrating a dispensing apparatus constructed in accordance with an embodiment of my invention and adjusted for use;

Figure 2 is a view in top plan of the 60 apparatus as herein embodied with the top or cover removed;

Figure 3 is a vertical sectional view taken longitudinally through the compartment for the envelopes;

Figure 4 is a vertical sectional view taken longitudinally through the compartment for the letter sheets; and

Figure 5 is a detail view partly in elevation and partly in section of one of the 70 rollers as herein embodied.

As disclosed in the accompanying drawings, C denotes a container or receptacle of desired configuration and dimensions and which is provided with a hinged top T. 75 The interior of the container or receptacle C is divided into the compartments A and B by the partition P. The compartment A is of such dimensions to receive a pile X of letter sheets while the compartment B is of a size to receive a pile Y of envelopes.

A wall 1 of the container or receptacle C is provided thereacross with a slot 2 common to both of the compartments A and B and whereby each of said compartments is provided with a discharge opening or slot. The bottom 3 of each of the compartments A and B is inclined upwardly toward the wall 1, the high point of the bottom 3 of each of said compartments A and B terminating immediately adjacent the lower edge of the discharge opening or slot.

The compartment B which contains the pile Y of envelopes is of a length less than the length of the compartment A and the length of said compartment B is shortened by a transversely disposed partition P' suitably positioned therein. This partition P' provides the rear supplemental compartment B' which houses the flexible member or chain M interposed between the partition P' and the top T. The chain or member M is for the purpose of limiting the outward swinging movement of the top T. The compartment B' is also adapted to contain various accessories for use in connection with my improved dispensing apparatus, such as additional weights, reference to which will be hereinafter made in detail.

The lower marginal portion of the de- 110

livery slot of each of the compartments A and B is defined by an inwardly and upwardly directed or curved flange 4 which serves as a guide or deflector to facilitate the desired passage of a letter sheet or envelope through such slot.

Disposed transversely of each of the compartments A and B at the upper portion thereof and in relatively close proximity to the wall 1 of the container or receptacle C is a shaft 5, said shaft extending exteriorly of the container or receptacle C and provided with an operating knob 6.

Loosely engaged with each of the shafts 5 are the corresponding end portions of the elongated parallel members or side arms 7, said members or side arms being connected adjacent their opposite end portions by the cross member 8. Rotatably supported by said members or side arms 7 outwardly of the cross member 8 is a shaft 9 to which is suitably fixed a roller R.

The shafts 5 and 9 have fixed thereto the sprocket wheels 10 with which is associated an endless sprocket chain 11 whereby the shaft 9 is in driven connection with the shaft 5. Also fixed to each of the shafts 5 is a ratchet wheel 12 with which coacts a resilient dog or pawl 14. The dog or pawl 14 and the associated ratchet wheel 12 cooperate in a manner to permit free rotation of the shaft 5 in one direction but to lock the shaft 5 against rotation in the opposite direction.

The roller R, as herein disclosed, comprises two overlying disks 15 of soft cellular material, preferably sponge rubber, said disks being suitably fixed to a hub 16 mounted upon the central portion of a shaft 9 for rotation therewith. By the use of these soft cellular disks 15, the cells or open pores in the periphery thereof result in the formation of a vacuum as said roller, upon rotation, engages the uppermost letter sheet or envelope of the pile X or Y, respectively, so that the feeding movement of a single sheet or envelope toward the desired delivery slot is materially facilitated.

By having the members or side arms 7 pivotally engaged with a shaft 5, said members or arms, together with the parts carried thereby, may be swung readily and conveniently into an upward or inoperative position to facilitate the application of a pile of letter sheets or envelopes within the respective compartments A and B.

To further assure the proper engagement of a roller R with its coacting pile X or Y, each of the cross members 8 is provided with an upwardly disposed post 17 with which is adapted to be engaged the weighted members 18 herein disclosed as annular. If preferred, the post 17 may have a laterally and substantially horizontally disposed extension 17' with which the weighted mem-

bers are directly engaged and the post 17 may be engaged with the cross member 8 by the thumb screw 19. By this means, the post 17, or more particularly its extension 17', may be swung to different positions to best comply with the requirements of practice.

Each of the cross members 8 has hingedly engaged therewith, as at 20, a substantially rigid flap 21, said flap being normally disposed toward the wall 1 and of a length to terminate in close proximity thereto. This flap 21 provides an effective means to guide a letter sheet or envelope toward the delivery slot and to prevent said letter sheet or envelope from passing above said slot and thereby hindering or interfering with the desired delivery thereof.

The flap 21 in the compartment A differs from the flap in the compartment B to the extent that it is provided at its opposite side portions with the outwardly directed flat fingers or extensions 22, said fingers or extensions being adjusted on a desired curvature.

The rear wall 23 of the compartment A and the rear wall of the compartment B as afforded by the partition P' each has hingedly engaged therewith, as at 24, the upper marginal portion of a flap 25, preferably of metal, and which flap 25 is adapted to bear down upon the pile X or Y and which contact of the flap 25 with a pile further assures the single delivery of a letter sheet or envelope. Either or both of the flaps 25 may be provided with an upstanding post 26 with which are engaged the weighted members 27 also herein disclosed as annular. The weighted members 27 are employed to assure the desired action of a flap 25 upon a pile.

From the foregoing description it is thought to be obvious that a dispensing apparatus constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A dispensing apparatus of the class described comprising a container provided with a discharge slot and having a bottom leading to the lower marginal portion of said slot, a shaft disposed across said container, means exterior of the container for rotating the shaft, arms supporting within the container for swinging movement in a vertical direction, a roller supported between said

arms and adapted to contact with the top of a pile within the container, a driving connection between the shaft and the roller, and a guide flap pivotally supported between said 5 arms and disposed in a direction away from the roller, said flap having free swinging movement.

2. A dispensing apparatus of the class described comprising a container provided 10 with a discharge slot and having a bottom leading to the lower marginal portion of said slot, a shaft disposed across said container, means exterior of the container for rotating the shaft, arms supported within the 15 container for swinging movement in a vertical direction, a roller supported between said arms and adapted to contact with the top of a pile within the container, a driving connection between the shaft and the roller, 20 a guide flap pivotally supported between said arms and disposed in a direction away from the roller, said flap having free swinging movement, the side portions of the guide

flap being provided with outwardly directed flat extensions.

3. A dispensing apparatus of the class described comprising a container provided with a discharge slot and having a bottom leading to the lower marginal portion of said slot, a shaft disposed across said container, means exterior of the container for 25 rotating the shaft, arms supported within the container for swinging movement in a vertical direction, a roller supported between said arms and adapted to contact with the top of a pile within the container, a driving connection between the shaft and the roller, a cross member connecting the arms inwardly of the roller, a guide flap pivotally 30 connected to the cross member and disposed in a direction away from the roller, said flap having free swinging movement toward or from the bottom of the container.

In testimony whereof I hereunto affix my signature.

WILLIAM T. HUNTER.
